BUMPER FOR TRUCKS

Ted L. Cline, Rush Springs, Okla., assignor to Cline Industries, Rush Springs, Okla.

Filed Mar. 3, 1971, Ser. No. 120,784

Term of patent 14 years

Int. Cl. D12—16

U.S. Cl. D12—169

FIG. 1 is a front elevational view of a bumper for trucks showing my new design;

FIG. 2 is a top plan view thereof;

FIG. 3 is a rear elevational view thereof;

FIG. 4 is a bottom plan view thereof;

FIG. 5 is a right end elevational view thereof;

FIG. 6 is a left end elevational view thereof; and

FIG. 7 is a sectional view thereof taken along line 7—7 of FIG. 2.

The characteristic feature of my design for a bumper for trucks resides in the convexly rounded ends located at opposite ends of two arm portions of the bumper, with one of the convexly rounded ends of each arm lying toward the center of the bumper and over a hitch plate, and the other convexly rounded end of the respective arm lying at one of the outer ends of the bumper.

I claim:

The ornamental design for a bumper for trucks, substantially as shown and described.
